DESIGN FOR A MILK CAN CART

Otto W. Leonard, Lynchburg, Ohio

Application March 8, 1945, Serial No. 118,327

Term of patent 7 years

(Cl. D14—3)

To all whom it may concern:

Be it known that I, Otto W. Leonard, a citizen of the United States, residing at Lynchburg, in the county of Highland and State of Ohio, have invented a new, original, and ornamental Design for a Milk Can Cart, of which the following is a specification, reference being had to the accompanying drawing, forming part thereof.

The drawing is a perspective view of a milk can cart showing my new design.

I claim:

The ornamental design for a milk can cart, as shown.

OTTO W. LEONARD.
